UNITED STATES PATENT OFFICE.

PAUL VON BOECKMANN, OF NEW YORK, N. Y.

LUNG-EXERCISING APPARATUS.

SPECIFICATION forming part of Letters Patent No. 734,252, dated July 21, 1903.

Application filed July 2, 1902. Serial No. 114,076. (No model.)

To all whom it may concern:

Be it known that I, PAUL VON BOECKMANN, a citizen of the United States, residing in the borough of Manhattan, city, county, and State 5 of New York, have invented certain new and useful Improvements in Lung-Exercising Apparatus, of which the following is a specification.

My invention relates to apparatus for exercising the lungs, so as to develop their capacity and to bring the blood into a healthful condition.

I have found that by properly-gaged breathing exercises the condition of the blood can be improved materially, but that care must be taken not to produce too great a strain, because in the latter case injurious effects are liable to follow.

My invention relates particularly to that 20 class of apparatus in which the person is supposed to blow into a recipient of variable capacity, the change in capacity being generally effected by the use of a float or bell which dips more or less into a liquid, according to the 25 amount of air blown into the apparatus. In an apparatus of this class as the bell or movable part of the recipient rises the resistance opposed to further movement remains practically unchanged, and the beneficial result 30 is very slight.

Therefore my present invention has for its object to provide means whereby the resistance opposed to the movement of the recipient upon the blowing in of air will be increased gradually.

Several of the constructions which I have devised for carrying out my present invention are illustrated in the accompanying drawings, in which each of the figures is a central 40 sectional elevation of a different form of my invention. It will be understood that I do not restrict myself to these specific constructions, but that the features of improvement are pointed out in the appended claims and that 45 any construction upon which one or more of said claims can be read will to a greater or lesser extent present the same advantages as the construction shown in the drawings.

In Figure 1, A indicates the base upon 50 which rests the container or shell B, adapted to be filled with water or other liquid and to receive the inverted cup or movable section

C, preferably provided with a lip C', engaging the upper edge of the shell B. D is the air-inlet tube, which extends within the shell 55 B and within the movable section C, so as to terminate above the level of the liquid, the lower end of said tube being provided with an elbow which connects with a tube D', adapted for connection with a flexible tube 60 provided with a mouthpiece, this being a well-known construction, which I have not deemed it necessary to show in the drawings. From the top of the movable section C is suspended a vessel or bucket E, which is open at the 65 top, so that it may become filled with the liquid contained in the shell B. The connection of this vessel with the movable section C may be made by means of a chain F, engaged with a hook G on the movable section, 70 and this also affords a means of adjusting the connection by simply engaging the hook with different links of the chain. Any other connection may be employed; but preferably the connection should be adjustable. As air is 75 blown into the upper portion of the movable section C this section will rise and will carry the receptacle E with it. As long as the said receptacle E is below the surface of the liquid the resistance opposed to the rising of the 80 movable bell C will not vary appreciably; but as soon as the receptacle E rises above the level of the liquid an additional resistance will be opposed to the further movement of the section C, and this resistance will increase 85 gradually as the said receptacle E rises out of the water or other liquid. The person breathing into the apparatus will therefore be compelled to breathe harder and harder in order to bring about a further movement of the section C; but as the resistance increases gradually all danger of an excessive strain and of injurious results consequent thereupon is avoided. By adjusting the distance between the hook G and the top of the receptacle E, I 90 can vary the time which it takes the said receptacle to rise above the liquid, and thus the action of the entire apparatus may be readily adjusted.

In the construction shown in Fig. 1 the adjustment of the receptacle E, which furnishes the gradually-increasing resistance, can be effected only by removing the bell C from the apparatus, inasmuch as the adjusting de-

vice is located inside the bell and is not accessible when the apparatus is in operation. To enable the resistance device to be adjusted from the outside, I may employ a construction such as shown in Fig. 2, where the base A, the shell B, the inverted cup C, and the air-supply tube D are constructed substantially as in Fig. 1, except that the movable section C is provided at the center with an aperture or with a sleeve C², through which is adapted to pass the stem H' of the resistance H, which latter is in the form of a cylinder and may be solid or hollow. A screw I or any equivalent device, serves to rigidly connect the bell C with the resistance device H, and the stem H' may be provided with a scale or graduation indicating, for instance, the distance from the top of the bell to the top of the resistance-body H. The action in this case will be the same as described with reference to Fig. 1—that is, the resistance will not increase appreciably as long as the resistance-body H is entirely submerged in the liquid; but as the said body gradually emerges from the liquid the resistance will increase progressively. The same result is obtained in a somewhat different manner in the construction represented in Fig. 3. Here I employ a construction almost identical with that in Fig. 1 except that the chain F', instead of carrying the receptacle E, has secured thereto at regular intervals plates or disks J, which form the resistance-body. It will be understood that upon the rising of the movable section C the plates or disks J will one by one rise above the liquid, and the resistance will thus be increased gradually; but this increase will be a stepwise increase instead of being absolutely gradual, as in the construction illustrated by Figs. 1 and 2—that is, the resistance will be practically unchanged while the bell C rises from the position shown in Fig. 3 until the uppermost disk J reaches the surface. Then the resistance will be increased by an amount which corresponds to the difference between the weight of said disk J and the weight of a body of water of the same volume. The resistance will then remain unchanged at this figure until the second disk J reaches the surface, and thus the increase will progress step by step.

In Figs. 4 and 5 I have shown two constructions in which the resistance-body is located exteriorly of the bell C. The general structure of the apparatus is the same as before described except that the air-inlet tube D² is disposed centrally. In Fig. 4 the top of the movable section C is provided with a hook or eye G' upon the outside to receive one end of a chain F², which leads over stationary pulleys K and carries weights or resistance-plates J', preferably at regular intervals. The lowermost of these plates is adapted to rest on the ground or on any suitable support, and as the movable body C rises all the plates J' move down except the one which rests on the

stationary support. It will be understood that these plates J' are in the nature of a counterbalance for the movable section C. As soon as the second plate from the bottom rests on the stationary bottom plate the amount of the counterbalance is reduced and the resistance to further upward movement of the movable section C is increased. A further increase takes place when the third plate J' is arrested by contact with the plate below, and thus the resistance opposed to the rising movement of the section C increases step by step until all the plates J' are in engagement with each other. In Fig. 5 the movable section C is flattened at the top to form a seat for the lowermost one of a series of resistance-plates J², spaced apart and held in proper relation to each other by some means which does not interfere with the movement of the plates relatively to each other. For instance, a chain F³ may be employed, and it will be readily understood that when the movable section C rises sufficiently to bring the lowermost plate J² against the next plate above the resistance will be increased, and a further increase will occur when the continued rise of the movable section C brings the second plate J² against the top plate.

What I claim as new, and desire to secure by Letters Patent, is—

1. A lung-exercising apparatus, comprising a stationary receptacle or shell adapted to contain a liquid, a movable section or bell arranged to dip into said liquid, and provided at the top with a central attaching device upon its inner surface, a chain adjustably connected with said attaching device, a resistance-body suspended from said chain and consisting of an open receptacle arranged to dip into the liquid, and means for conveying the air into the upper portion of the bell.

2. A lung-exercising apparatus, comprising a stationary receptacle adapted to contain a liquid, a movable section or bell arranged to dip into said liquid, a bucket suspended from the top of said bell and adapted to dip into said liquid, and means for conveying air into the upper portion of the bell.

3. A lung-exercising apparatus, comprising a stationary receptacle or shell adapted to be filled with a liquid, a movable section or bell adapted to dip into said liquid, a resistance device suspended from the top of the bell, and adapted to dip into said liquid, and means for conveying air into the upper portion of the bell.

4. A lung-exercising apparatus comprising a stationary receptacle or shell adapted to contain a liquid, a tube which has a discharge-orifice above the level of the liquid and which is adapted to receive the air exhaled by a person, a movable section or bell arranged to dip into said liquid and to confine the air blown through the said tube, and adjustable means arranged to dip into the liquid for opposing a gradually-increasing resistance to

the rising movement of the bell so that the effort of the lungs in lifting the said movable section may be gradually increased.

5. A lung-exercising apparatus, comprising a stationary receptacle or shell adapted to be filled with a liquid, a movable section or bell arranged to dip into said liquid, a resistance-body adjustably connected with the bell to move therewith and arranged to dip into the liquid so as to oppose a varying resistance to the movement of the bell as the said resist-

ance - body emerges more or less from the liquid, and means for conveying air into the upper portion of the bell.

In testimony whereof I have signed my ¹⁵ name to this specification in the presence of two subscribing witnesses.
